CLAIM

I claim the ornamental design for a ceiling fan, as shown and described.

DESCRIPTION

FIG. 1 is a bottom, front perspective view of the ceiling fan, for which a bottom, rear perspective view is identical.

FIG. 2 is a top, front perspective view of the ceiling fan, for which a top, rear perspective view is identical.

FIG. 3 is a bottom plan view of the ceiling fan.

FIG. 4 is a front elevational view of the ceiling fan, for which rear elevational, left side elevational, and right side elevational views are identical.

FIG. 5 is a top plan view of the ceiling fan; and,

FIG. 6 is another bottom, front perspective view of the ceiling fan, for which a bottom, rear perspective view is identical.

The ceiling fan as shown in FIGS. 1-6 has four-way (90°) rotational symmetry, except for disclaimed portions.

The broken lines represent environment and form no part of the claim.
